UNITED STATES PATENT OFFICE.

CHARLES LEVER, OF BOWDON, COUNTY OF CHESTER, ENGLAND.

EXCITING-CIRCUIT FOR DYNAMO-ELECTRIC MACHINES.

SPECIFICATION forming part of Letters Patent No. 291,209, dated January 1, 1884.

Application filed February 19, 1883. (No model.) Patented in England May 3, 1882, No. 2,092; in France November 3, 1882, and in Belgium November 4, 1882.

To all whom it may concern:

Be it known that I, CHARLES LEVER, a subject of the Queen of Great Britain, residing at Bowdon, in the county of Chester, England, 5 have invented a new and useful Improved Method and Apparatus for Exciting Continuous-Current Dynamo-Electric Machines, of which the following is a specification.

My invention is to be employed when continuous currents are used with the lamps constructed and regulated on the shunt-circuit principle, and where the carbon points are separated before the current is sent through the lamp, such currents are generated by what 10 is called a "self-exciting continuous-current dynamo-machine"—e. g., a series dynamo. If, for example, a number of such lamps are placed in series or single circuit, the carbon points on the lamps being separated, the only path for 15 the electric current is through the shunt-circuits on the electro-magnets or solenoids in the lamps; but the resistance of these shunt-circuits would be so great that the said dynamo-machine could not excite itself through this 20 resistance. One method of obviating this difficulty is as follows: It is well known that when a dynamo-electric machine is excited the iron parts of the machine become strongly magnetized, and the magnetism of any of these 25 parts—whichever part is most convenient—is, according to my invention, utilized to attract 30 an armature. Figure 1 shows such an arrangement. D is a dynamo-machine, of which B B' are the terminals, to which are connected, 35 for example, four lamps, L, as shown. A is an armature capable of moving on a pivot or fulcrum at A'. Z is the iron loop of the dynamo D. The figure shows the lamps in action. A resistance, R, about equal to the 40 resistance of the four arcs L, is connected as follows, viz: from + binding-screw B to the armature A. A short thick wire connects metal stud S with the negative binding-screw B'.

C is a spring-contact, shown in section at 45 Fig. 2, where A is the armature, through which passes a large screw, F, having a hollow part for the reception of the end of spiral spring J, and forces the contact-piece C, which has a stem guided through screw F, onto the metal 50 stud S, connected to the negative terminal B' on the dynamo D. The screw F serves to ad-

just the tension of spring J. Before the lamps are lighted, the carbons being apart, the armature A is moved by hand or by means of the spring H, which is adjustable by a nut, K, on 55 pillar M, so that contact-piece C makes connection with stud S, thus completing the shunt-circuit through resistance R. When, however, the armature of the dynamo commences to revolve, the machine excites itself through 60 shunt-circuit and resistance R until the iron loop Z becomes sufficiently magnetized to attract armature A, thus causing the said shunt-circuit to be broken, whereupon all the current will flow through the main circuit and 65 lamps L, thus causing the shunt electro-magnets or solenoids in the lamps to instantly form their arcs. The spring H should be adjusted so that the armature A will be attracted by the iron loop Z of the dynamo when said dynamo 70 is excited to the minimum electric energy necessary for actuating the magnets of the lamps; hence the armature A will be held firmly to the loop Z by the magnetism until such magnetism sinks below the minimum energy, 75 when the spring H will move such armature and automatically close the circuit through the resistance R.

When it is not desirable or convenient to utilize the magnetism of the iron loop or other 80 iron projection of the dynamo to allow the dynamo-machine to excite itself, as already described, an electro-magnet or solenoid, preferably wound with a resistance equal to that of the arcs L, is connected in the dynamo shunt-circuit, and an armature, A, capable of moving on a pivot, A', fixed at one end of the armature A, is used. At the end of the armature A opposite to the pivot A' is a metal piece, C, sliding through the said armature, 85 and a spring, J, presses this metal piece C upon a metal stud, S. (Shown in Figs. 3 and 4.) The electro-magnet or solenoid E in the shunt-circuit has the ends of its coils—which are of coarse wire having, as already stated, a resistance about equal to that of the lamps L— 90 connected one to the pivot A' of the armature A, and the other to one of the binding-screws of the dynamo-electric machine, or to the binding-screws B B' on the insulating-plate I, and thence to the dynamo, the said electro-magnet E, armature A, and metal stud S being 95 100

fixed on the plate I of the insulating material—such as wood or vulcanite—the metal stud S being made flush therewith. When the metal piece C, sliding through screw F on the armature A, is resting on the metal stud S, and the said metal stud is connected by a wire of low resistance, as shown at Fig. 3, to the other binding-screw of the dynamo-machine, the exciting shunt-circuit is complete, viz: from 5 the positive binding-screw of the dynamo through the coils of the electro-magnet E or solenoid to the pivot A' of the armature A, through the armature and metal piece C to the metal stud S and to the negative binding-screw of the dynamo, or vice versa. When the shunt-circuit is thus completed and the dynamo has excited itself, the armature A will be attracted by the said electro-magnet E or solenoid, the screw F having been so adjusted that the armature A will not be attracted until the dynamo has sufficiently excited itself and the metal piece C will leave its metal stud S, thus 10 breaking the shunt-circuit and allowing the current generated by the dynamo to actuate the lamps L, as before. The latter device may be placed at or in the electric lamp itself by arranging an electro-magnet or solenoid (in this case wound with a resistance preferably equal to the arc) in derivation to the arc; but such arrangements would not be practicable 15 with a number of lamps, on account of the difficulty of causing all the devices to break the shunt-circuits at the same time. The said device may be fixed in any other convenient place and connected with the dynamo, so that the lamps can be started from any desired place. I do not limit myself to the devices 20 above described—as, for example, a simple switch or key may be used to form this exciting shunt-circuit, and to break the said shunt-

circuit by hand when the dynamo has excited itself; but this arrangement, not being automatic, would necessitate some skill on the part of the operator in order to ascertain to a nicety when the dynamo had sufficiently excited itself for him to break the shunt-circuit by releasing the key or moving the switch. The devices hereinbefore described are, however, when once adjusted, automatic. 45

Having now described the nature of this invention and the manner in which it is or may be carried into effect, I claim— 50

1. In combination with a series dynamo-electric machine and with shunt electric-arc lamps arranged in series, a shunt or derived circuit having a resistance equal to said lamps, and through which the current passes for the purpose of exciting the dynamo, and a circuit-breaker for breaking the said shunt-circuit when the dynamo has excited itself, 55 and causing the current to pass through the magnets of the lamps to form their arcs, substantially as specified. 60

2. In combination with a series dynamo-electric machine and with shunt electric-arc lamps arranged in series, the magnet E in a shunt-circuit from the dynamo D, and having a resistance about equal to the arcs, the pivoted armature A, spring J, contact-piece C, stud S, and wire connections, substantially as 65 specified, whereby the armature will be moved when the dynamo has excited itself, thus breaking said shunt-circuit and causing the current to pass through the magnets of the lamps and to form their arcs, substantially as 70 specified. 75

CHARLES LEVER.
